UNITED STATES PATENT OFFICE

111,017

DESIGN FOR A DRESS

Louise Decker, New York, N. Y.

Application July 11, 1938, Serial No. 78,402

Term of patent 3½ years

To all whom it may concern:

Be it known that I, Louise Decker, a citizen of the United States of America, residing in New York City, in the Borough of Manhattan, county and State of New York, have invented a new, original, and ornamental Design for a Dress, of which the following is a specification, reference being had to the accompanying drawing, forming part thereof, wherein,

The trim on the skirt and sleeves of the dress is of fringe.

I claim:

The ornamental design for a dress, substantially as shown and described.

LOUISE DECKER.
